PROCESS FOR PRODUCING CELLULOSE

Joaquin Julio de la Roza, Sr., Plandome, N. Y.,
assignor to de la Roza Corporation, Wilmington,
Del., a corporation of Delaware

Original application December 17, 1931, Serial
No. 581,636. Divided and this application Jan-
uary 4, 1934, Serial No. 705,210

9 Claims. (Cl. 92—7)

This invention relates to the process for producing cellulose, and is a division of my copending application Serial No. 581,636, filed December 17, 1931.

5 It has for an object to provide for the continuous treatment of cellulose bearing material so as to accomplish the production of cellulose therefrom at a greatly accelerated rate.

10 Another object consists in providing for treatment of cellulose bearing material at a much higher volumetric density than has heretofore been practical, whereby the efficiency and output are greatly enhanced.

15 Another object consists in providing means for assuring rapid and complete uniform penetration of chemical into the raw material prior to heating to maximum temperature, whereby the treatment time is reduced and the quality of the product improved.

20 Another object consists in providing apparatus which is relatively simple and inexpensive to manufacture and yet highly productive and efficient in operation.

25 A further object consists in providing certain improvements in the form, construction and arrangement of the several parts, and in the steps followed, whereby the above named and other objects may effectively be attained.

30 A practical embodiment of the apparatus is diagrammatically represented in the drawing, which representation, when taken in connection with the following description, will set forth my invention for the clear understanding of those skilled in the art.

35 In the treatment of cellulose bearing materials, such as wood and various members of the grass family, it has been customary to charge the treating vessels or digesters with a mixture of the fibrous material and chemical solution, introduced together or separately; and thereafter to apply heat for the treatment, then discontinue the heat, discharge the contents, and repeat the operation by again charging, etc. This procedure has involved serious limitations arising from the interruption of treatment at the time of each discharge, from the lack of uniform quality in the product due to defective and uneven penetration of the raw material by the chemical, and from the limited amount of fibrous cellulose bearing material treated in a given vessel or digester at a single time. My invention overcomes these limitations by providing for continuous treatment which may proceed for hours or months, if desired; and for greatly increasing the volumetric density of the charge during treatment. Heretofore a charge containing about nine pounds of bone dry material per cubic foot has been substantially the maximum in the case of wood, and about half of that in the case of bagasse, corn-

stalks, and the like, whereas my invention provides for charging to a volumetric density of, say, twelve to fifteen, or even twenty pounds of bone dry material per cubic foot.

5 Referring to the drawing, which includes one diagrammatic figure, a treating vessel or digester is denoted by 1. The form of this vessel is quite unusual but its general construction may substantially follow any well known or approved kind of digester. It should be provided with any usual or desirable equipment such, for instance, as gauges, valves, thermometers, heating appliances, etc. The vessel may either be stationary or of the rotating type.

10 At one end a valve 2 is provided which is operable by the handle 3 for discharging the contents from the vessel. This valve may be of usual or suitable form, construction and operation.

15 The representation of the vessel in the drawing is broken away intermediate its ends to indicate that it is intended to have a greater proportionate length than shown in the drawing; and I may say that I prefer to make this vessel of relatively great length and small diameter. 20 This may be illustrated by a length of, say, a few hundred feet, and a diameter of, say, a few feet. Such a proportion greatly facilitates the continuous procedure which features my invention and tends to insure that all the material is 25 uniformly treated and occupies a uniform period of time during passage through the treating vessel. It will be understood that the particular dimensions and proportions of the vessel may be varied to suit different factors arising from various methods of treating various materials. 30

35 The end of the vessel opposite the valve 2 is provided with an opening 4 which is in communication with a tube 5 that is restricted in area as it approaches the vessel. The drawing 40 is intended to represent a tube taking the form of a truncated cone, but I should say that my invention contemplates any manner of restricting or partially inhibiting the movement of material through the tube toward the vessel, 45 whether such manner involve a regular or irregular restriction of cross sectional area or arrangements for increasing surface friction within the tube, or otherwise.

45 The larger end of the tube communicates with 50 a cylinder 6 in which is located a piston 7 that is designed to be reciprocated by suitable mechanism, not shown. Two positions of the piston are represented, by way of example, in full and dotted lines. This mechanism is illustrated as 55 one of many suitable kinds adaptable for the purpose of feeding the material.

55 The cylinder 6 has a port 8 which is in register with a feed or hopper 9, which may be of 60 any well known or approved form.

The vessel 1 has ports 10 and 11 that are connected by a circulating pipe or by-pass 12 in which are located strainers 13 and 14, check valves 15 and 16, and manual valve 17. The 5 check valve 15 operates so as to permit entry into the vessel and the check valve 16 operates so as to permit movement from the vessel. The valve 17 is operable so as to permit movement in either direction. The particular construction 10 and arrangement of these circulating and feeding parts may, of course, be varied to suit different conditions. In the drawing I have shown only one pipe 12, but it will be understood that additional pipes, correspondingly arranged, 15 may be provided to connect additional ports in the vessel. As the construction of such additional pipes and ports would, naturally, be the same as that shown, it is deemed unnecessary to illustrate them. This pipe 12 permits circulation of the solution from near the discharge end of the vessel to near its inlet end and thus facilitates the action of the chemical 20 and the movement of the material. It also has a certain advantage by way of providing means for affecting the temperature within the vessel. The valve 17 may be used for the injection of chemical into the vessel, as may be required, which chemical will pass through the pipe 12 and enter the vessel through the valve 15. The 25 valve 17 may also be used to permit discharge from the vessel of an excess of chemical, if conditions call for it, though it will be understood that, during the operation of the apparatus, the valve 17 is normally closed. The 30 strainers 13 and 14 are calculated to withhold the passage of any large particles of the material through the circulating pipe 12.

The parts hereinabove mentioned are intended to be connected by suitable means such as, 40 for example, flanges and bolts, which are diagrammatically represented in the customary way, and which it is regarded as unnecessary to designate by reference numerals.

In operation, the fibrous cellulose bearing material, such as bagasse, cotton linters, cotton 45 stalks, flax stalks or waste, wood, or any of the suitable undergrowth-woods, grasses or canes, etc., may be broken up or shredded in any of the many well known or approved manners and 50 conveyed, for instance by a conveyor belt, to the hopper 9. This material may be mixed with the desired chemical solution, as by use of a tank or spraying apparatus, prior to its conveyance to the hopper; or it may be mixed with 55 such solution at the time it is deposited in the hopper; or otherwise. I prefer to spray it as it enters the hopper because, the less the mixture is exposed to the air, the less will be the oxidation.

60 The material is continuously passed into the hopper and drops therefrom into the cylinder 6 at a point in front of the piston 7 when the latter is wholly or partly retracted. The reciprocating action of the piston will continuously force the material through the tube 5 toward and into the vessel 1. The frictional 65 resistance of the tube 5 will cause the material to be more tightly compacted or compressed as it is urged through the tube so that it will enter 70 the vessel in a condition of quite high volumetric density, e. g., about twenty to thirty or more pounds of dry material to the cubic foot. This density will vary according to different conditions existing in different treating procedures, but I ordinarily prefer to use something 75

over thirty pounds to allow an abundant margin of safety against blow-outs. In order to facilitate this compacting of the material, I prefer to, at the outset, drop a somewhat compact wad of material through the hopper into the cylinder, which wad will act as a plug in the tube 5 and thus initiate the compressing or compacting action described. Such a wad may be made either manually or by any suitable compressing device which is at hand. Compression of the material to substantially the density indicated will cause each successive charge or batch advanced by the piston to act as a sort of plug or cork while in the tube 5 and the entrance to the vessel 1 so as effectively to prevent any escape of the contents from the vessel back into the tube under the influence of the pressure within the vessel. On the other hand, after each successive batch of the material has been forced into the vessel, it will expand or break up so as better to circulate and intermix with the chemical solution. In these respects, the relative cross sectional size of the apparatus at the cylinder 6, the opening 4 and the body of the vessel 1 are of some importance with respect to the best 25 operation of the apparatus and I have found that the said proportions, substantially as shown in the drawing, are satisfactory although, of course, various changes in these factors as well as in the particular shape of the parts may be 30 made while retaining the apparatus in operative form and arrangement. It will be observed that, in the drawing, the diameter of the body of the vessel 1 is about twice the diameter of the opening 4, so that the cross sectional area 35 of the former would be about four times that of the latter. Experimental test and practical operation has proved this ratio of one to four to be well within the preferred limits which, for the best operation, should not greatly vary from 40 the ratio named.

This action of the piston on the material not only compacts and moves the material toward and into the vessel 1, but it also brings about a thorough mixing of the chemical solution with the fibrous material by forcing the chemical through pressure into the cells, so as to insure that the chemical has access to and reaches every portion of the material, prior to heating to maximum temperature, thereby preventing 45 injury to the material, expediting the operation, and improving the quality of the product.

As the material is thus compacted and forced through the tube 5, the action may become so severe as to press or squeeze some of the chemical solution out of the material; in which event this solution may escape backwardly between the piston and the walls of the cylinder 6.

At the outset of the operation the discharge valve 2 is closed and it is retained in closed position until the vessel has been charged to the intended degree or density, which condition may be indicated by a suitable thermometer pressure gauge or other recording instrument provided on the vessel. When this stage is reached, the 60 valve 2 is opened and regulated so that it remains open the proper amount to insure the same rate of discharge, during the continuous 65 operation of the apparatus, as the rate of charge of the vessel through the tube 5.

70 It should also be said, though it will probably be understood, that the heating appliances for the vessel are set in operation at the outset of the procedure so that a proper treating temperature is maintained within the vessel, as by 75

5 injection of steam, jacketing, electricity, or any other approved way. If the vessel is of the rotating type, as hereinabove indicated, the rotary motion, which may be either continuous in one direction or oscillatory, will have a substantial tendency to agitate the contents of the vessel and thereby promote the treatment.

10 It will be seen that, as already indicated, chemical solution may be admitted or discharged through the valve 17 to or from the vessel 1, so that the predetermined and desirable proportion of the mixture of material and chemical solution is maintained in the vessel.

15 It will be observed that this apparatus, through the cooperation of the feeding device and the frictional resistance of the tubular inlet, compacts the material to such a density as satisfactorily to establish a seal during operation while permitting the continuous feed of the material into the digester. The apparatus also permits digestion at a very high density which promotes efficiency by, among other things, preventing the fresh material from mixing with the partly digested material; and promotes economy in various respects including a saving in heating medium, chemical, recovery processes, radiation losses, labor, time, and avoidance of the re-use of chemical in the form of black liquor or the like. The form of inlet which I have shown complements the form of feeding device to enable a very rapid compacting of the entering material and, thus, the prompt formation of a very satisfactory seal, while likewise permitting the ready passage of the material 20 through the inlet and into the digester proper.

25 The above described apparatus and method provide for a continuous procedure whereby the material is fed into the hopper 9 and forced by the piston 7 through the treating vessel under predetermined conditions as to treating chemical, volumetric density, and temperature or pressure. I contemplate that the apparatus may be operated both day and night for any reasonable period of time. The treated material, as it is 30 discharged from the vessel, may be subjected to the ordinary finishing steps, or to a further chemical treatment, or may be shipped to some other point for use or further treatment. In case an additional treatment under the action 35 of chemical and temperature is desired, the discharged material may be fed into another similar apparatus and continuously treated as hereinabove described.

40 I do not intend the invention to be limited as to the particular kind of cellulose bearing material treated, or as to chemical or temperature employed, but intend the same to have broad application as a continuous procedure in the manufacture of cellulose, preferably under conditions of very high volumetric density of 45 charge. Furthermore, it will be understood that various changes may be resorted to in the form, construction, and arrangement of the several parts, and in the steps followed, without departing from the spirit and scope of my invention; and hence I do not intend to be limited to the details herein shown or described, except as they may be included in the claims.

50 Having thus described my invention, what I claim is:

55 1. A continuous method of producing cellulose including the step of treating cellulose bearing material with a chemical in a digestion stage at

a volumetric density in excess of 12# per cubic foot (dry basis).

60 2. A continuous method of producing cellulose including the steps of continuously charging and discharging a digesting vessel with cellulose bearing material and maintaining the charge in said vessel at a volumetric density substantially in excess of 12# per cubic foot (dry basis).

65 3. A continuous method of producing cellulose including the step of charging the cellulose bearing material successively through compression and digesting steps and treating the material with a chemical in the digestion step at a volumetric density in excess of 12# per cubic foot (dry basis).

70 4. A continuous method of producing cellulose comprising the step of charging the cellulose bearing material in a compressed column to a digestion stage wherein the column is disintegrated, and treating the material with a chemical while maintaining said material at a volumetric density in excess of 12# per cubic foot (dry basis).

75 5. A continuous method of producing cellulose including the steps of charging the cellulose bearing material in a compressed column to a digestion stage wherein the column is disintegrated, and exhausting the occluded air from the material in the compression step, and treating the material with a chemical at a volumetric density in excess of 12# per cubic foot (dry basis) in the digestion step.

80 6. A continuous method of producing cellulose including the steps of spraying the material with the liquid at a low temperature and exhausting the occluded air from the material in a compression step, introducing the material thence into an elongated digestion step and subjecting the material to the digestion action of chemicals at a higher temperature and at a pressure relatively lower than the pressure existing in the compression step.

85 7. A continuous process for digesting fibrous or cellular material comprising the steps of adding a digesting liquor in a preliminary step, passing the material thence to a digesting step in which the material is subjected to a digesting liquor at a higher temperature than that in the preliminary step, and maintaining the material under digestion at a volumetric density in excess of 12# per cubic foot (dry basis) during the digestion thereof.

90 8. A continuous method of continuously digesting fibrous or cellular material comprising the steps of charging the material to be digested to a digestion stage, adding a chemical thereto, effecting the digestion of the material at a volumetric density in excess of 12# per cubic foot (dry basis), and discharging the digested material from the digestion stage, and controlling the input and discharge of material to be digested to maintain predetermined digestion conditions.

95 9. A method of continuously digesting fibrous or cellular material comprising the steps of discharging the material to be digested to a digestion stage, adding a chemical thereto, effecting the digestion of the material at a volumetric density in excess of 12# per cubic foot (dry basis), and discharging the digested material from the digestion stage, and controlling the input and discharge of material to be digested to maintain predetermined digestion conditions.

JOAQUIN JULIO DE LA ROZA, Sr.
